[57] CLAIM

The ornamental design for a multifunction necklace
container, substantially as shown and described.

DESCRIPTION

FIG. 1 is an enlarged perspective view of a multifunction
necklace container showing my new design;

FIG. 2 is an enlarged front elevational view thereof;

FIG. 3 is an enlarged side elevational view of the right
side of the container as viewed in FIG. 2. The left side
of the container is a mirror image of the right side;

FIG. 4 is an enlarged top plan view thereof;

FIG. 5 is an enlarged bottom plan view thereof;

FIG. 6 is an enlarged perspective view of a multifunction
necklace container showing a modified form of my
new design;

FIG. 7 is an enlarged front elevational view thereof;

FIG. 8 is an enlarged side elevational view of the right
side of the container as viewed in FIG. 7. The left side
of the container is a mirror image of the right side;

FIG. 9 is an enlarged top plan view thereof; and

FIG. 10 is an enlarged bottom plan view thereof.
